WATER GAUGE GLASS CLEANER

Dana C. de Hart, Hillsborough, Calif.

Application July 21, 1953, Serial No. 369,296

2 Claims. (Cl. 73—324)

The present invention relates to improvements in a water gauge glass cleaner. It consists of the combinations, constructions, and arrangement of parts, as herein-after described and claimed.

It is a common practice to provide a water gauge on a boiler, or the like, for the purpose of indicating the level of the water prevailing in the boiler. In the usual construction, the gauge includes a tubular glass, which has its opposing ends placed in communication with the interior of the boiler by water and steam valves. Thus, in normal operation, a column of water is permitted to flow from the boiler to the tubular glass, thereby disclosing the water level of the boiler.

However, it is a well-known fact that the tubular glass of such a water gauge will become discolored over a period of time, thus precluding an observer from gaining a clear view of the water level in the glass. Accordingly, it is necessary to dismantle the gauge, clean the bore of the tubular glass; and thereafter reassemble the various parts of the water gauge.

As the cardinal object of this invention, it is proposed to provide an attachment that is adapted to be secured to a conventional water gauge, without requiring any changes in the construction of the latter. This attachment includes a brush arranged in the bore of the tubular glass of the gauge, which may be reciprocated to thoroughly clean the interior of the glass, without requiring removal of the latter after initial assembly. This is a greatly article, and inasmuch as it does not required any change in present installations, its field of usefulness is thereby enlarged.

Other objects and advantages will appear as the specification continues. The novel features of the invention will be set forth in the claims hereunto appended.

Drawing

For a better understanding of my invention, reference should be had to the accompanying drawing, forming part of this application, in which:

Figure 1 is an elevational view of a boiler having a conventional water gauge coupled thereto, with my glass cleaner attachment operatively connected to a water shut-off valve of the installation;

Figure 2 is a view similar to Figure 1, but illustrating a tubular housing removed so as to allow the cleaner brush to be reciprocated in the gauge; and

Figure 3 is an enlarged transverse sectional view taken along the vertical plane III—III of Figure 1.

While I have shown only the preferred form of my invention, it should be understood that various changes, or modifications, may be made within the scope of the annexed claims without departing from the spirit thereof.

Detailed description

Referring to the drawing in detail, I have shown a fragmentary portion of a boiler A having a tubular glass B mounted exteriorly thereof. The lower end of this glass is placed in communication with the boiler by a water shut-off valve C and a pipe 10, while its upper end is

2

coupled to the boiler by a steam valve D and a pipe 11. It will be apparent that when both of these valves are opened the level 12 of a column of water in the tubular glass B will be the same as the level 12a of the water contained in the boiler.

In its structural features, the water shut-off valve C is provided with a rotatable and axially-movable stem 14 having a valve 14a at its inner end, which is adapted to bear against a seat in the body 15 when this valve is closed. Moreover, the body 15 has a threaded opening 16 in its bottom (see Figure 3), which normally has a pet cock 17 screwed thereto.

For the purpose of permitting the interior bore 18 of the tubular glass to be cleaned, I have provided a brush or glass cleaner E therein. This brush may be fashioned from wire, fibre glass, or other suitable bristles, and has a flexible shaft or handle F fastened thereto so as to extend downwardly through the opening 16 of the water shut-off valve. Inasmuch as the longitudinal axis 19 of the tubular glass B, when extended in the manner shown in Figure 3, will pass through the valve stem 14, a section 20 of the flexible shaft may curve laterally around one side of this stem to allow the shaft to be moved up and down for cleaning operations.

It will be noted that in my installation a nipple 21 is threaded into the opening 16, instead of the pet cock 17. Moreover, a T 22 is coupled to this nipple and has the lower section 23 of the flexible shaft projecting down-through. As shown, the pet cock 17 is screwed into the horizontal branch 24 of the T. In order to provide a water-tight housing around the lower section 23 of the flexible shaft F, a tube or housing G is removably screwed into the bottom of the T, as clearly disclosed in Figure 1. This tube has a closed end 25 at its bottom.

When installing my attachment, the valves C and D are closed, as shown in Figure 2. Thereafter, the glass B and the pet cock 17 are removed from the water shut-off valve C. It will be found convenient to run a copper wire (not shown) up through the opening 16 until it comes out at the top of the valve C. Then the wire may be attached to the lower end of the flexible shaft F so as to draw the latter around the valve stem 14 and thence down through the threaded opening 16, with the flexible shaft projecting below this valve for ready grasping by an individual.

Then the nipple 21, T 22 and pet cock 17 may be installed in the manner illustrated in Figures 1 and 2, either before or after the flexible shaft F is drawn through the water shut-off valve. The flexible shaft may be pulled down until the brush E is confined within a flanged fitting 26 of the valve C, thus concealing the brush from exterior view. After replacing the glass B and screwing the tube G into the T 22, the valves C and D may be opened. Of course, the bristles of the brush are spaced apart sufficiently to allow water from the boiler A to flow through the brush until the water level 12 in the tube B corresponds with the water level 12a in the boiler.

Having thus described the various parts of my water gauge glass cleaner, the use thereof is summarized briefly as follows:

Initially, the water shut-off and steam valves C and D, respectively, are closed, as suggested in Figure 2. The pet cock 17 may be opened to allow the column of water in the tubular glass B to be drained. Then the tube G is unscrewed from the T 22, thus exposing the lower section 23 of the flexible shaft F. The latter may be reciprocated up and down until the bore 18 of the glass is clean. The brush may be left at the lower part of the tubular glass, as shown in Figures 1 and 3 so as to be concealed, and then the tube G screwed into the lower end of the T. After these steps have been completed, the valves C and D are reopened.

I claim:

1. The combination with upper and lower spaced-apart valves, each having a stem; and a tubular water gauge glass having its ends coupled to the valves; the gauge glass having a bore communicating with chambered interiors of the valves; the lower valve defining a body fashioned with an opening located on the opposite side of its stem from that of the gauge glass; of a glass cleaner attachment comprising: a glass cleaner reciprocably mounted in the bore of the tubular glass for cleaning the latter; a flexible handle having one end thereof secured to the glass cleaner, and its other end projecting through the opening of said lower valve body, and extending below the latter to constitute a handle section disposed exteriorly of the lower valve; the flexible handle being curved laterally to one side of the lower valve stem; a nipple secured 10 to the wall defining said opening in the lower valve to extend therefrom; a T coupled to this nipple; the flexible handle extending through the nipple and the T to a position below the latter; a tubular housing telescoped over the projecting section of the flexible handle, and being removably secured to one end of the T; the lower end of the tubular housing being closed; the T including a horizontal branch; and a drain pet cock coupled to this branch of the T.

2. The combination with upper and lower spaced-apart valves, each having a stem; and a tubular water gauge glass having its ends coupled to the valves; the gauge 25 glass having a bore communicating with chambered interiors of the valves; the lower valve defining a body fashioned with an opening located on the opposite side of

5
